(57) CLAIM

The ornamental design for a bottle with lid, as shown and described.

DESCRIPTION

FIG. 1 is a perspective view of the bottle with lid.

FIG. 2 is a right side view of the bottle with lid;

FIG. 3 is a left side view thereof;

FIG. 4 is a front side view thereof;

FIG. 5 is a back side view thereof

FIG. 6 is a top view thereof; and,

FIG. 7 is a bottom view thereof.

The broken lines in the drawings represent portions of the bottle with lid that form no part of the claimed design.
